UNITED STATES PATENT OFFICE.

JOHN HENRY WYNN, OF BIRMINGHAM, ENGLAND.

EXPANSIBLE CHAIN OF THE KIND USED AS BRACELETS.

1,326,816.

Specification of Letters Patent. Patented Dec. 30, 1919.

Application filed June 5, 1918. Serial No. 238,348.

To all whom it may concern:

Be it known that I, JOHN HENRY WYNN, a subject of the King of Great Britain, residing at 42-46 Hylton street, in the city 5 of Birmingham, England, have invented certain new and useful Improvements in Expansible Chains of the Kind Used as Bracelets, of which the following is a specification.

The invention provides the hereinafter described and claimed improvements in expansible chain of the kind used as bracelets and comprising a succession of pairs of outer links connected by a succession of middle links, with which may be combined 15 thickening up or distancing links for the purpose of obtaining a broader pattern of chain, some of said links containing coiled springs operating in compression to provide the resiliency in the chain.

20 The invention provides for a maximum amount of expansion, preferably without fully compressing the springs, and uses a single coiled spring in each outer link only. The essential feature of the invention is 25 the employment in combination with each spring, aforesaid, of a connecting piece which is substantially a straight bar having oppositely bent right angled ends, the one end of this piece providing an abutment for 30 the one end of a spring, and the other end of said piece positively connecting with a middle link, preferably to the extreme inner end of the latter, the action of the chain in expanding being that as each two middle links 35 (working between a pair of outer links) move apart the two springs contained in the links of each outer pair are put into further compression in reverse directions.

The invention is illustrated by the accompanying sheet of drawings applied to a narrow pattern of chain, and to a wider pattern using thickening up or distancing links.

Figure 1 is a plan of a chain portion partly expanded.

45 Fig. 2 is a sectional plan of Fig. 1.

Fig. 3 is a transverse section of Fig. 2 on the dotted lines B—B, looking to the right.

Fig. 4 shows a plan section of a pair of outer links separate.

50 Fig. 5 is a plan section of a middle link separate.

Fig. 6 shows three views of a connecting piece separate.

Fig. 7 is a plan of a chain portion using 55 thickening up or distancing links.

With reference to Figs. 1 to 6 *a* are the

outer links, *d* are the middle links, *e* are the connecting pieces, and *f* the springs. Two outer links *a* are oppositely coupled to form a pair by a transverse bar *g* applied 60 to the under faces of said links so that both links of a pair form a rigid piece, but said bar may be the last piece applied in assembling the chain while the various links, 65 springs, and connecting pieces are suitably held in assembled positions. Each link *a*, which is hollow to contain one of the coiled springs *f*, is entirely closed except for its full length inner side *a*², which is left open. Each spring *f* under normal compression 70 extends approximately the full interior length of each link *a*.

The middle links *d* may be either hollow or solid as they do not contain springs, but each at its extreme ends is formed with a 75 transverse hole *d*². Two of said middle links slidably work within the parallel space *h* between two links of an outer pair in a well known manner.

The connecting piece *e* is substantially a 80 straight bar having oppositely bent right angled ends *e*², *e*³. The end *e*³ of this piece engages a transverse hole *d*² in a middle link *d*, and the end *e*² of said piece provides an abutment for the one end of a spring *f*. Two 85 of these connecting pieces are used for each pair of outer links to form resilient connectors between the middle links *d* and the outer links *a*, each connecting piece operating against one spring only, and those of a 90 pair of outer links in opposite directions against the springs. That part of each connecting piece between its right angle ends works within the open inner side *a*² of its 95 particular outer link *a*, and therefore said connecting piece in its sliding movement within the outer link on expanding the chain will move against the one end *a*³ of an outer link as a stop limiting the expansion of the chain and insuring that the springs *f* shall 100 never be fully compressed, that is to say, shall not be unduly strained, which has the effect of maintaining the effective resiliency of the spring action. If an abnormal expansion of the chain is desired the sliding 105 movement of the connecting pieces need not be stopped, or limited, but allowed to take place until the full compression of the springs has been effected in which case the sliding movement of the connecting pieces 110 may still be guided by sliding through gaps in the ends *a*³ of the outer links, which gap

engagements will prevent displacement of the middle links from alinement with the spaces h .

5 The right angled end e^3 of the connecting piece may pivot within the transverse hole d^2 of a middle link, and may be secured in its engagement therewith by turning in the extremity of said end after engagement with the middle link, as shown at e^4 .

10 The operations of the springs and connecting pieces will be clear from the drawings, it being obvious that if the chain length represented by Figs. 1 and 2 contracts two middle links d will approach each other and abut at their ends in the middle of the length of the spaces h , and each end e^2 of a connecting piece will move up to the one end of an outer link as a stop against the action of the spring.

15 20 In Fig. 7 the springs and connecting pieces c are combined with the outer and middle links to operate in exactly the same manner as described with reference to Figs. 1 to 6, but in order to provide a broader pattern 25 of chain thickening up or distancing links are used; for example i is a thickening up link to the pair of outer links a a , same being rigidly fixed to the bar g and longitudinally slotted between its ends so that the 30 right angled end e^3 of the connecting piece may freely thread therethrough and work therein, while m and n are thickening up links to the middle links d d , same being arranged so that the right angled ends e^3 of 35 the connecting pieces also engage them, said right angled ends being made longer than in the case of the narrower pattern chain, Figs. 1 to 6, for this purpose.

Having now described my invention what 40 I claim and desire to secure by Letters Patent is:—

1. An expansible chain comprising a succession of pairs of outer hollow links, a plurality of middle links movably mounted 45 between the pairs of outer links, a spring enclosed in each outer link, and two connecting pieces between the springs of each pair of outer links and the ends of the middle links between the pairs of outer links, each 50 connecting piece consisting of a straight bar having reversely bent angular ends, one

angular end engaging the inner end of each middle link and the remaining angular end engaging one end of one of the springs, the connecting pieces working in reverse directions relatively to the springs in each pair of outer links. 55

2. An expansible chain comprising a succession of pairs of outer hollow links having connecting means between them, a succession of middle links working between the pairs of outer links, a spring mounted for free compression in each outer link, and two connecting pieces, one for each outer link, the connecting pieces being freely 60 movable in the inner portions of the outer links and having reversely bent angular ends, the connecting pieces being individually connected at their inner ends to the middle links between each pair of outer 65 links and also having their outer ends engaging the springs in each pair of outer links and movable in reverse directions to oppositely compress the springs in each pair of outer links. 70

3. An expanding chain of the class specified comprising a succession of pairs of outer links having inner open sides, each pair of outer links having transverse connecting means between them, a succession of 75 middle links between the pairs of outer links, a spring mounted in each outer link and free to move longitudinally in the latter, and a connecting piece consisting of a straight bar having its inner end angularly 80 bent and pivoted to the end of one middle link between each pair of outer links and its outer end also angularly bent and extending into the one outer link and engaging one end of the spring in the latter, the 85 connecting pieces being reversely arranged and also reversely compressing the spring and movable in the inner open ends of the 90 pairs of outer links.

In testimony whereof I have hereunto 95 set my hand in presence of two subscribing witnesses.

JOHN HENRY WYNN.
